BERNHARD BEHR, OF DRESDEN, GERMANY.

ADDING-MACHINE PROVIDED WITH CHAIN DRIVE.

1,096,012.

Specification of Letters Patent.

Patented May 12, 1914.

Application filed August 30, 1911. Serial No. 646,899.

To all whom it may concern:

Be it known that I, BERNHARD BEHR, of 19 Hamburgerstrasse, Dresden, in the Kingdom of Saxony, in the German Empire, 5 company director, have invented certain new and useful Improvements in Adding-Machines Provided with Chain Drive.

This invention relates to an adding machine provided with chain drive, according to which those parts of the chain which operate the figure disk consist of members having spring-operated pawls or of a collapsible and spring-operated rack. By this arrangement the advantages of an adding 15 machine provided with rack driving mechanism are combined in a single machine with those of a machine having a chain drive.

In the constructional form of the machine in which the operating part of the 20 machine consists of a collapsible spring-operated rack, it is necessary to mount the rack on parallel arms, which are normally in an inclined position, for the purpose of avoiding the dead point between the driving 25 tooth and the tooth to be engaged. In this manner the efficiency is substantially increased, and it is possible simultaneously to operate a large number of tens without any trouble, which in the restricted method generally employed is in many cases impossible.

In the accompanying drawing Figure 1 is a longitudinal section of the adding machine, omitting irrelevant parts; Fig. 2 is a 35 section on the line $x-x$ of Fig. 1; Fig. 3 is a section through the guiding plate for the chains; Fig. 4 shows the part of the chain above the guiding plate to a larger scale, the chain consisting of operating members, figure disks, and the rod-like parts of the 40 chain connecting these two together; Fig. 5 is a plan of the same part of the chain; Fig. 6 is a section on the line $y-y$ through one of the operating members; Fig. 7 is a 45 section on the line $z-z$ through the flat connecting rod between the operating and figure members; Fig. 8 shows a constructional form in which the part of the chain corresponding to the operating members is 50 replaced by a collapsible operating rod.

The machine between the two guiding rollers c for the chain is completely covered by the plate g . Above the surface of the plate g the chains are provided and are 55 guided in separate guides by guiding grooves being milled in the plate g so that

on both sides guides g^1 are formed. The chains consist of separate parts, which are each adapted for a certain operation. One part corresponds to the figure disks m . The 60 part connected thereto is formed by the flat rod p ; the next part is formed by the operating part i having folding pawls. To these are connected the usual chain members d , the last member of which is connected 65 by a spring o to the end of the row n of operating members. The spring o tensions the chain. As the chain only moves through a distance equal to the part m provided with the numbers, the chain therefore reciprocates; the connecting member between the members for the figures and the operating members, which moves in a straight line from one guiding roller c to the other, can consequently be replaced by a flat rod p . 70 The chain members m provided with figures lie on one another in the manner of tiles and form eyes for inserting a pin by means of which the chains can be adjusted. The locking members n , with which locking teeth 75 provided on a shaft engage in the usual manner, are released on depression of the releasing key, so that the chain is again brought into the original position by the action of the spring f . The part to the left 80 of the rod p is formed by the operating members i ; these are provided with spring-operated pawls r . Each separate operating member consists of a frame in which are rotatably mounted the spring-operated 85 pawls r in such manner that on the movement of the chain to the right the pawls operate the figure disks b , but on releasing the chain, that is, on the return movement, they 90 pass over the figure disks as the rotatable 95 pawls are folded on their pivots (see Fig. 4).

According to the constructional form shown in Fig. 8, the operating members are replaced by a rack t , which in arms w forming a parallelogram can be folded on 100 the rod s . A spring v raises the rack t when the chain is moved to the right, so that the figure disk b is operated, whereby a projection z provided behind one of the arms w prevents the arms w from assuming 105 a vertical position. On the movement of the chain to the left the rack t is depressed and the teeth are put out of operation. On the employment of a rack instead of a chain having toothed members, the machine is 110 somewhat longer, but behind the figure disk sufficient space remains free for the move-

ment of the tens. By placing the parallelogram formed by the rods *s* and racks *t* and the arms *w* in an inclined position the dead point between the engaging tooth and the tooth to be driven is avoided whereby the simultaneous movement of a large number of tens can be effected smoothly.

Having now particularly described and ascertained the nature of my said invention, 10 and in what manner the same is to be performed, I declare that what I claim is:—

In combination with a toothed figure or like wheel of a calculating machine, a reciprocating chain composed of links pivotally connected with each other, rollers about 15

which the chain is trained, a contractile spring connecting the ends of the chain, a second contractile spring connected with one end of the chain and with a fixed part, teeth pivotally mounted on said links, and a spring for each tooth for projecting the same into the path of the teeth of said figure wheel, substantially as described.

In testimony whereof I have hereunto set my hand in presence of two subscribing witnesses.

BERNHARD BEHR.
